(57) **CLAIM**

The ornamental design for a folding umbrella stand, as shown and described.

DESCRIPTION

FIG. 1 is a perspective view of the umbrella stand of the present invention;

FIG. 2 is a front elevation view thereof;

FIG. 3 is a top plan view thereof;

FIG. 4 is a bottom view thereof;

FIG. 5 is a side view thereof;

FIG. 6 is a front elevation view of the umbrella stand of the present invention in its folded configuration; and,

FIG. 7 is a side view of the umbrella stand configured as in FIG. 6.

The broken lines shown in the drawings are directed to environment, and are for informational purposes only and form no part of the claimed design.
